BOWLING GLOVE

Donald J. Carter, Miami, Fla., and Frank P. Esposito, Paramus, N.J., assignors to National Athletic Supply Corporation, Paramus, N.J.

Filed June 3, 1974, Ser. No. 475,834

Term of patent 14 years

Int. Cl. D2—06

U.S. Cl. D2—361

Fig. 1

Fig. 2

Fig. 3

Fig. 4

Fig. 5

Fig. 6

Fig. 7

FIG. 1 is a top perspective view of a bowling glove showing our new design;

FIG. 2 is a top plan view thereof;

FIG. 3 is a bottom plan view thereof;

FIG. 4 is a side elevational view thereof as seen from the top of FIG. 3;

FIG. 5 is an end elevational view as seen from the left-hand end of FIG. 4;

FIG. 6 is a side elevational view as seen from the left-hand side of FIG. 5; and

FIG. 7 is an end elevational view as seen from the left-hand end of FIG. 6.

We claim:

The ornamental design for a bowling glove, substantially as shown.
